HEAT CONTROL DEVICE

Charles C. Prince, Raleigh, N. C.

Application November 12, 1947, Serial No. 785,237

1 Claim. (Cl. 236—99)

1

My present invention relates to an improved thermostatic oil flow control of the type especially adapted for use with space heaters and so arranged as to automatically cut off the flow of oil by actuation of the conventional oil flow valve when the room temperature reaches a predetermined point.

A more even control of the burner operation and resultant maintenance of room temperature will bring about a saving in oil and also a more comfortable temperature in the air of the room.

In the accompanying drawings I have illustrated one complete example of the physical embodiment of my invention according to the best mode I have thus far devised but it will be understood that various changes and alterations may be made in the exemplified structure within the scope of the appended claim.

In the drawings:

Fig. 1 is a top plan view of the device of my invention as used in connection with an oil flow valve assembly.

Fig. 2 is a side elevational view of my device.

Fig. 3 is a transverse vertical sectional view.

Fig. 4 is a front elevational view.

Fig. 5 is a longitudinal vertical sectional view at line 5—5 of Fig. 3.

Fig. 6 is a horizontal sectional view at line 6—6 of Fig. 5.

Referring now to the drawings I have illustrated the present preferred embodiment of the structure of my invention as used with a conventional valve casing having a cover 2 and an oil tube fitting 4 and provided with a valve stem actuator 6.

In my invention I employ an open bottom housing having a rear wall 8 and front wall 10 formed with an aperture 11 therein, and end walls 12 with cover 14.

A rearwardly extending flange 16 is normally secured by screws 18 to the valve casing, and within the housing I utilize a transverse bar 20 journaled in the walls of the housing and secured thereto rigidly is the thermostat arm 22 connected with the thermostat 24 of the bellows type. An actuator arm 26 abuts the thermostat and is positioned in the path of its expansive movement at 28. A pivoted support bar 30 supports the actuator arm and its valve contact arm and is journaled at 32 in the end walls of the housing.

A control bar 34 has a central U-crank 36 located under the thermostat arm 22 and the control bar is journaled at 38 in the end walls of the housing. A cotter pin 40 secures the free end of the bar in position and the other end has a control arm 42 formed with an inturned end 44 movable under the indicia plate 46 on the exterior of one side wall of the housing. The inturned end 44 frictionally engages the side wall of the housing to retain the arm in the desired position after it has been moved to agree with

2

the indicia plate 46. Thus if the control arm 42 is turned to move the thermostat closer to the arm 26 or further from the arm 26 the thermostat 24 will be caused to operate at a lower or higher temperature.

With the control bar set at the desired position to regulate the minimum temperature to be maintained, the thermostat will expand under any rise in temperature to rock the actuator arm and depress the valve contact arm to close the valve of the casing and shut off the supply of oil to the burner. As the temperature declines and the thermostat contracts the contact arm will raise allowing the oil to pass.

By this simple construction the desired constant temperature may be maintained on any conventional type of space heater, and being simple in operation and requiring no electrical connections may be installed and maintained by the most inexperienced person.

Having thus fully described my invention what I claim as new and desire to secure by Letters Patent is:

In a control for use with an oil flow valve for space heaters having a valve stem actuator and said control having a box-like housing provided with an open bottom adapted to receive the oil flow valve the improvement comprising, a bar journaled in the housing transversely thereof, a heat responsive element in the housing, an arm on one side of the element rigid with the bar, an actuator arm within the housing abutting the element on the opposite side thereof, a pivoted support bar journaled transversely of the housing below but parallel to said first bar, and said support bar being secured to and supporting said actuator arm, a control bar journaled transversely of the housing intermediate of and parallel with the two first said bars, a central U-shaped crank in said control bar adapted to abut the arm on the element, a control arm on the outer end of said control bar, adapted to coincide with indicia placed on the outside of said housing, whereby when said control arm is adjusted in relation to said indicia the crank in said control bar will engage the arm on said element to regulate the control of said oil flow valve.

CHARLES C. PRINCE.
